INVENTOR.

Franklin R. Robison
BY Everett & Rock, ATTORNEYS.

UNITED STATES PATENT OFFICE.

FRANKLIN R. ROBISON, OF GLOVERSVILLE, NEW YORK.

LAUNDRY-NET RECEPTACLE.

Application filed April 11, 1921. Serial No. 460,378.

To all whom it may concern:

Be it known that I, FRANKLIN R. ROBISON, a citizen of the United States, and a resident of Gloversville, in the county of Fulton and State of New York, have invented new and useful Improvements in Laundry-Net Receptacles, of which the following is a specification.

This invention relates to a receptacle for storing and sorting laundry nets. Heretofore fabric laundry nets, which are utilized in laundries to wrap or bundle articles of a given customer preparatory to placing them in the washers, have after use been tossed indiscriminately into piles upon a table or the floor, all sizes and colors being thrown into the same pile. The nets after use are wet and when so piled have no chance to dry and thereby rapidly deteriorate, and, all sizes of nets being thrown together, the operator wastes time and energy in picking over the nets in a pile to extract a net of the desired size and color.

The objects of the invention are to provide a receptacle of the character described in which the nets may be stored so as to be readily accessible to the operator at all times, and which will allow the nets to dry therein and protect them against loss or injury; to provide such a receptacle having separate compartments for the nets of various sizes and colors, whereby a net of a given size and color can be quickly obtained with a minimum expenditure of time and labor; to provide a receptacle of this character having separate receiving and discharging openings, the compartments being constructed with restricted discharge openings to allow the withdrawal of only a single net at a time; to provide a laundry net receptacle through which a constant circulation of air is obtained so as to dry the nets stored therein to prevent deterioration thereof; to provide such a receptacle having an enlarged receiving opening at the top thereof, and a restricted discharge opening at the bottom thereof, the nets descending by action of gravity from said receiving opening to the discharge opening in substantially the order in which they were thrown into the receiving opening, and only one of the nets being presented at the discharge opening at one time; and to obtain other results and advantages as may be brought out by the following description.

Referring to the accompanying drawing,

in which like numerals of reference indicate the same parts throughout the several views,

Figure 1 is a perspective view of a laundry net receptacle constructed in accordance with my invention, and

Figure 2 is a transverse vertical sectional view through the same.

Laundry nets are usually classified according to color into three groups, namely, light, dark and black, and the nets are usually made in three sizes commonly known as 12, 8 and 6. I have accordingly shown on the drawings a laundry net receptacle constructed to be used with three groups of colors, each group comprising nets of the three above-named sizes. The embodiment of my invention shown in the drawing comprises a bottom or base 1 which may be formed of any suitable material such as wood or metal, and two end pieces 2 which are vertically mounted at opposite ends of said bottom 1 in spaced and substantially parallel relation. Said end pieces 2 are connected at their top by a top strip 3, the side edges of the ends 2 inclining downwardly in opposite directions as at 4 and then converging inwardly and downwardly as at 5 to a point slightly spaced from the bottom 1, after which the sides of the ends diverge outwardly as at 6. A plurality of partitions 7 similar in construction to the end pieces 2 are arranged between the said ends in spaced and substantially parallel relation, the said partitions being so spaced as to form three series of different sized compartments 8 therebetween, each group of compartments comprising a compartment to receive the size 12 nets, another compartment to receive the size 8 nets and another compartment to receive the size 6 nets, the various groups being adapted to receive respectively the light, dark and black colored nets.

The sides of the receptacle are preferably of skeleton or open-work construction whereby a thorough circulation of air is obtained through the receptacle, and in the present instance I have shown the downwardly converging portions 5 of the ends 2 connected by strips of wire screen 9, the said screen extending from the lower ends of the inclined portions 4 of the ends and partitions 7 to the inner ends of the outwardly diverging portions 6 at the bottom of the receptacle, the said screen being secured to the ends 2 and partitions 7 in any suitable manner as by the attaching strips

10 which are tacked or otherwise secured to the said ends and partitions. It will thus be seen that the compartments 8 are open at their upper ends between the sides 9 and 5 the top strip 3 of the receptacle at both sides of the receptacle.

Doors 11 are hingedly connected as at 12 to the lower ends of the sides 9 of the receptacle and are adapted to swing outwardly and upwardly to permit access to the compartments 8 at the bottom thereof, said doors extending substantially half the length of the outwardly diverging portions 6, strips 13 being secured to the ends 2 and 15 partitions 7 at the bottom thereof and extending upwardly to within a short distance of the lower edges of the doors 11 to provide a space 14 between each of the doors and the strips 13 for the insertion of the fingers 20 of the operator to open the door and also for the circulation of air upwardly through the receptacle.

Furthermore, these doors frictionally engage any net or nets which tend to be inadvertently dragged out with a net being positively withdrawn, and thus obstruct the inadvertent withdrawal of more than desired.

In the use of the receptacle it is placed 30 upon the sorting table at which the articles to be laundered are sorted and wrapped in the nets, one operator being stationed at each side of the table in convenient position to throw nets into the open upper ends of the 35 compartment 8 and extract nets from the lower ends thereof. As the nets are removed from the bundles of articles, they are thrown by the operator or sorter into the compartment 8 corresponding to the color 40 and size of the net, and the nets in the receptacle fall by gravity toward the bottom thereof. The downwardly converging sides of the receptacle provide restricted discharge openings 15 at the points of intersection between the outwardly diverging 45 portions at the bottom of the receptacle and the lower edges of the sides 9 thereof as clearly shown in Figure 2 of the drawing. The discharge openings 15 are only sufficiently large to allow one or two laundry 50 nets to pass through the same at one time, and in order to remove a laundry net of a desired color and size the operator opens the door 11 at his side of the receptacle and pulls the lowermost net outwardly from the 55 bottom of the receptacle. The uppermost nets then gradually fall downwardly, and it will be seen that they will be presented at the discharge openings 15 in substantially the same order in which they are 60 thrown into the receiving openings at the upper ends of the compartments. The skeleton or open-work sides 9 of the receptacle allow a thorough and complete circulation of air through the same so as to dry the nets 65 while they are stored in the respective compartments.

partments, and the openings 14 at the bottom of the receptacle also allow the circulation of air upwardly through the same. With my laundry net receptacle it will be seen that with reasonable care the laundry 70 nets can be easily and quickly sorted so as to store the laundry nets of one color and size all together in one compartment, so that they are always conveniently accessible to the operator without the necessity of going through a pile of nets of all sizes and colors as is now necessary. The large receiving 75 openings for the compartments allow several of the nets to be thrown thereinto at one time and from both sides thereof, but the 80 downwardly converging sides 9 of the receptacle and the restricted discharge passages 15 guide the nets downwardly so that only one or two are presented at the bottom of the compartment at one time. 85

While I have shown and described one possible embodiment of my invention, it will be understood that this is for the purpose of illustrating the details thereof only, and that many modifications and changes can be 90 made in the detail construction of the invention by those skilled in the art without departing from the spirit or scope thereof. Therefore, I do not desire to be understood as limiting myself except as required by the 95 following claims when construed in the light of the prior part.

Having thus described the invention, what I claim is:

1. A laundry net receptacle including a 100 bottom, an end piece vertically mounted upon each end of said bottom, the side edges of said end pieces being inclined downwardly and outwardly in opposite directions for a short distance and then converging 105 downwardly and inwardly to a point slightly spaced from the said bottom, said side edges then diverging downwardly and outwardly to the bottom, side pieces for the receptacle connected between the said downwardly and inwardly converging portions of said end pieces, the top of the receptacle being open between said uppermost downwardly and outwardly diverging portions of the end pieces to form a receiving opening, and doors hingedly connected to the lower edges of said side pieces to close the bottom of said receptacle between the said lowermost downwardly and outwardly diverging portions of the end pieces. 115

2. A laundry net receptacle including upright end pieces having their side edges inclined downwardly and outwardly in opposite directions for a short distance and then converging downwardly and inwardly to a point spaced from the bottoms of said end pieces, the side edges then diverging downwardly and outwardly to said bottoms, side pieces for the receptacle secured to the 120 downwardly and inwardly converging por- 125

tions of the side edges of said end pieces, the top of the receptacle being open between said uppermost downwardly and outwardly diverging portions of the end pieces to receive laundry nets and the bottom of the receptacle being open between the lower ends of the side pieces to discharge the nets, and doors upon said downwardly and outwardly diverging portions of the side edges of the end pieces adjacent their bottom, said doors being hinged at their upper edges and free at their lower edges to drag upon a net being withdrawn from between the lower ends of the side pieces.

3. A laundry net receptacle including upright end pieces having their side edges converging downwardly and inwardly to a point spaced from the bottom of said end pieces and then diverging downwardly and outwardly to said bottom, partitions between said end pieces similar and parallel thereto, and side pieces secured to the downwardly and inwardly converging portions of the side edges of said end pieces and partitions, the top of the receptacle having a receiving opening and the bottom a discharge opening between said side pieces. 15
